UNITED STATES PATENT OFFICE.

GEORGE P. REINTJES, OF KANSAS CITY, MISSOURI

TILE LINING FOR CYLINDRICAL KILNS.

Application filed January 10, 1927. Serial No. 160,140.

This invention relates to fire brick linings for cement kilns, ore roasting furnaces and the like. Heretofore kilns of the general character mentioned have commonly been lined with inwardly-tapering fire brick having no locking relationship other than that of the conventional keystone of tapering form used in the erection of arches, and the use of the smooth faced tapering brick necessitated the temporary support by individual bracing of practically all of the brick from the crest downward on each side to points not far short of the horizontal plane of the axis of the kiln. The setting of a lining of fire brick or tile of the conventional type mentioned, with the necessity of bracing a multiplicity of its units is slow and costly, and my object is to provide shodded lining tile which, with an interlocking relation, can be laid or set as easily as ordinary tile and require only about two braces in each ring of tile, instead of a brace for each tile except the topmost or key tile of the ring, upward from points about thirty degrees above the horizontal center of the kiln.

By the provision of sets of key tile of reversed type, the intermediate tile can set so that each sustains the tile superimposed upon it, this being especially advantageous in the setting of the tile in the upper half of the kiln as it avoids the necessity of using many braces as hereinbefore adverted to.

With the objects mentioned in view, the invention consists in certain novel and useful features of construction and combinations of parts as hereinafter described and claimed; and in order that it may be fully understood, reference is to be had to the accompanying drawings, in which:

Figure 1 represents an end view of a kiln equipped with a lining embodying the invention.

Figure 2 is a fragmentary plan view with the shell of the kiln broken away.

Figure 3 is a perspective view of one of what I term the intermediate tiles.

Figure 4 is an end view of the same.

Figure 5 is a perspective view of one of the two sets of key tile employed in the lining.

Figure 6 is a side view of the same.

Figure 7 is an end view of the same.

Figure 8 is a perspective view of one of the other sets of key tile of the lining.

Figure 9 is a side view of the same.

Figure 10 is an end view of the same. Referring now to the drawings in detail, 1 represents the metal shell of a kiln for cement making or ore roasting furnaces, 60 these shells being of large diameter and of relatively great length. Such shells must be protected from the intense heat to which their contents are subjected and are therefore customarily lined with fire brick or tile. 65

As hereinbefore suggested it is common to line them with smooth tapering fire brick and the setting of such tile is slow and costly. In lieu of the common tile mentioned I propose to employ tile which are stepped or 70 shouldered so as to interlock together at their abutting faces, all of the tile thus interlocking together except certain key tile of which I prefer to employ four sets, each set 75 consisting of two tile.

The tile, including the key tile, are set to form rings 2, adjacent rings abutting at their sides as indicated by Figure 2.

At diametrically opposite points are sets of key tile 3, and at right angles to such sets 80 of key tile are sets of key tile 4, and between and interlocking with each key tile 3 and 4 and with each other are intermediate tile 5.

The opposite sides of all of the tile are 85 parallel, and this is true of the ends of the tile. The opposite edges of all of the intermediate tile converge inwardly toward the axis of the shell, and this statement also applies as to the key tiles. Each of the latter 90 at one edge extends at a slight angle to its opposite edge, that is to say, one face or side of each key tile is slightly wider than the other face of said tile, the bevel edge thus produced being indicated at 6 on tiles 3, as 95 said tiles are of identical form and proportion, one of each pair being reversed with respect to the other so that it may be wedged into place and thus act to exert force laterally upon the abutting key tile and the intermediate tile.

Each of the key tiles 3 at its edge where it abuts an intermediate tile is stepped and the step is corrugated to provide a tongue 7 and a groove 8.

Each of the tiles 4 at the edge where it abuts its companion key tile is bevelled at 9 to correspond with the bevelled edges 6 of the tiles 3, and the other edge of each tile 4 where it abuts an intermediate tile has a 110 corrugated step constituting a tongue 10 and a groove 11.

Each intermediate tile has corrugated but reversely facing steps at both edges to provide tongues 13 and grooves 14, one step facing inwardly and the other outwardly.

5 In setting the tile the lower pair of tiles 3 are first placed in position in the shell with their bevelled edges abutting and their shoulders or steps facing upwardly. Intermediate tiles are then interlocked with said 10 key tiles and with each other until the lower half of a ring is about completed. The tiles 4 are then placed in position, the lower pair interlocking with the immediately underlying intermediate tiles, and the additional 15 intermediate tile are built up on tiles 4 and upon each other until the topmost ones have attained a position about sixty degrees above the horizontal axis of the shell, about which time the topmost tiles are braced by 20 wands "W" or the like secured upon a support "S" arranged within the shell, an elevated support as indicated being desirable because the shells approximate eleven feet in diameter. With the braces or wands in 25 place, any tendency of the series of tiles extending upwardly and inwardly from the key tiles 4, slide inward and downward, will be prevented, and when this bracing has been accomplished the remainder of the in- 30 termediate tiles are braced in position and finally the topmost pair of key tile are set, it being recalled that these key tiles are bevelled at their abutting or straight edges so that one of each pair acts as a wedge, any 35 suitable means being resorted to, such as a cementitious material, not shown, serving to guard against the wedge members of the key tiles from being crowded out of position, it being apparent that this possibility 40 of dislodgment of such key tiles has relation only to those of the endmost rings of the lining. Instead of securing such wedging tiles by cement or the like, they may obviously be secured by pins "P" extending 45 through the shell and into the wedging tile of each set, as indicated at one point on Figure 1, or by any equivalent means.

To accommodate kilns of the character under consideration which do not vary a great 50 deal in diameter, the tongues of the various tiles will fit the grooves of engaging tile with a little play so that tiles of standard size may be employed to form the rings in the shells of such different diameters, provided a few intermediate tiles slightly different in width from edge to edge be provided 55 to be used with the standard size tiles in making a setting for any particular shell, that is to say, a few tiles slightly narrower 60 from edge to edge may be used in conjunction with the standard tiles for a minimum diameter shell, whereas with a shell with maximum diameter, it will be necessary to use a few tiles of greater width from edge 65 to edge than the standard size. If the sizes

vary greatly, properly sized tiles for the same will be provided, I have found that the vast majority of tiles employed may be of one standard size, and that the necessity of manufacturing and maintaining large stocks 70 of tiles of several different sizes will be unnecessary.

From the above description it will be apparent that I have produced a lining for cement kilns and the like which embodies 75 the features of advantage set forth as desirable in the statement of the objects of the invention, and which may be modified in minor particulars within the principle and scope of the appended claims. 80

What I claim is:

1. A tile lining for kilns, comprising sets of key tiles having edges in wedge relation and their opposite edges stepped, and intermediate tiles having their opposite edges 85 stepped and in interlocking relation with each other and the stepped edges of the key tiles.

2. A tile lining for cylindrical shells, comprising sets of key tiles having their adjacent edges smooth and in abutting relation and their other faces stepped, and intermediate tiles stepped at both edges and interlocked together at such edges and to the stepped edges of the key tiles. 90

3. A tile lining for cylindrical shells, comprising two sets of diametrically opposite key tiles, the sets being at right angles, each being composed of two pairs of abutting tile smooth at their abutting edges and shouldered at their opposite edges, and interlocking intermediate tiles between and interlocked with adjacent members of the two sets of key tiles. 100

4. A tile lining for cylindrical shells, comprising sets of key tiles having their adjacent edges smooth and in abutting relation and their other faces stepped; and intermediate tiles stepped at both edges and interlocked together at such edges and to the stepped edges of the key tiles, the abutting edges of the key tiles being bevelled and one forming a wedge between one of the intermediate tiles and the other key tile. 105

5. A tile lining for cylindrical shells, comprising two sets of diametrically opposite key tiles, the sets being at right angles, each set being composed of two pairs of abutting tile smooth at their abutting edges and shouldered at their opposite edges, and interlocking intermediate tiles between and interlocked with adjacent members of the two sets of key tiles, the abutting edges of the key tiles being bevelled and one forming a wedge between one of the intermediate tiles 110 and the other key tile. 120

In witness whereof I hereunto affix my signature.

GEORGE P. REINTJES.
